UNITED STATES PATENT OFFICE

EMMETT F. CARTER, OF SCHENECTADY, NEW YORK, ASSIGNOR TO GENERAL ELECTRIC COMPANY, A CORPORATION OF NEW YORK

CONTROL SYSTEM

Application filed October 22, 1925. Serial No. 64,376.

My invention relates to systems for controlling the connections of electric circuits, and has for its principal object the provision of an improved means for producing a predetermined sequence of operations with a definite time interval between successive operations.

It is frequently desirable to change the connections of a circuit in a manner to maintain the circuit alternately opened and closed during successive time intervals predetermined to suit the requirements of the particular apparatus to be controlled. In accordance with my invention, this result is produced by means comprising an energy storage device that is utilized to predetermine the time interval between opening and closing of an electric valve adapted to control the change in circuit connections.

My invention will be better understood from the following description when considered in connection with the accompanying drawing and its scope will be pointed out in the appended claims.

Referring to the drawing, the single figure thereof shows a control system wherein my invention has been embodied.

This figure shows a relay device 1 which is provided with a contact member 2 for interconnecting the conductors 3 and with an operating coil 4 adapted to be supplied with current from a source 5 through an electric valve 6 comprising a grid 7 interposed between an anode 8 and a cathode 9. An energy storage device shown as a condenser 10 is connected between the grid 7 and cathode 9. A resistor 11 is connected in shunt to the condenser 10. The relay 1 is provided also with a contact member 12. Heating current is supplied to the cathode 9 from a source 14. A relay 15 comprising an operating coil 16, a contact member 17 and retarding means, shown as a dash pot 18, is adapted to be operated in response to current supplied from the source 14 through the contact member 2 of relay 1. In the closed or upper position of the relay 1, current is supplied to the condenser 10 from a source 19 through the contact member 12 and a resistor 20. In the open-

12 is adapted to cooperate with the contact member 17 of relay 15 for connecting the source 19 directly to the condenser 10. Throughout the specification and claims, the valve 6 is described as open when it transmits sufficient current to operate the relay 1 and as closed when the current transmitted is incapable of operating this relay.

The operation of the arrangement will be readily understood if it be assumed that the relays 1 and 15 are in their illustrated open positions. Under these conditions, the source 19 is disconnected from the condenser 10, the condenser is discharging at a rate predetermined by the adjustment of the resistor 11 and the negative potential applied to the grid 7 is gradually decreasing. When this potential has attained a predetermined value, the valve 6 opens and the relay 1 is operated to its closed position thereby interconnecting conductors 3, producing closure of relay 15 and connecting the condenser to the source 19 through resistor 20.

With these connections, the condenser is charged at a rate determined by the adjustment of resistors 11 and 20 and the potential of grid 7 eventually attains a potential at which the valve 6 is closed. When this occurs, the relay 1 opens and full voltage of the source 19 is applied to the condenser 10 during a brief time interval determined by the delay in the operation of the relay 15 which is de-energized by opening of relay 1. The application of full voltage to the condenser during the latter part of its charging period is of advantage in that it ensures uniformity in the charges applied to the condenser during successive charging intervals. Opening of the relay 15 interrupts the circuit between the source 19 and condenser 10 and the sequence of operations previously set forth is repeated.

It will be observed that the time interval between opening and closure of the circuit 3 is determined by the retardation of relay 15 and by the rate at which condenser 10 is discharged through resistor 11 and that the time interval between closure and opening of the circuit 3 is dependent on the rate at which the condenser is charged by current supplied through the resistor 20. By suitable adjust-

ment of the resistors 11 and 20 any desired relation may therefore be established between these periods.

The embodiment of the invention illustrated and described herein has been selected for the purpose of clearly setting forth the principles involved. It will be apparent, however, that the invention is susceptible of being modified to meet the different conditions encountered in its use and I therefore aim to cover by the appended claims all modifications within the true spirit and scope of my invention.

What I claim as new and desire to secure by Letters Patent of the United States, is:

1. The combination of an electrical valve comprising a grid interposed between a cathode and anode, an energy storage device connected between said cathode and grid for controlling the conductivity of said valve, a circuit control device connected between said cathode and anode, and means responsive to the operation of said control device for predetermined the rate at which energy is supplied to said storage device.

2. The combination of an electrical valve comprising a grid interposed between a cathode and anode, an energy storage device connected between said cathode and grid for controlling the conductivity of said valve, a control device connected between said cathode and anode, means responsive to the operation of said control device in one direction for causing energy to be supplied to said storage device at one voltage, and means responsive to operation of said control device in another direction for causing energy to be supplied to said device at a different voltage.

3. The combination of an electrical valve including a grid interposed between a cathode and anode, an energy storage device connected between said cathode and grid for controlling the conductivity of said valve, a control device connected between said cathode and anode, means responsive to operation of said control device in one direction for causing energy to be supplied to said storage means during one predetermined time interval, and means responsive to operation of said control device to another position for causing energy to be supplied to said storage device during a different predetermined time interval.

4. The combination of an electrical valve including a grid interposed between a cathode and anode, an energy storage device connected between said cathode and grid for controlling the conductivity of said valve, a control device connected between said cathode and anode, means responsive to operation of said control device in one direction for causing energy to be supplied to said storage means during one predetermined time interval, means responsive to operation of said control device to another position for causing

energy to be supplied to said storage device during a different predetermined time interval, and means for dissipating the energy of said storage device at a predetermined rate.

In witness whereof, I have hereunto set my hand this 21st day of October, 1925.

EMMETT F. CARTER.
